UNITED STATES PATENT OFFICE.

WILLIAM A. LORENZ, OF WEST HARTFORD, CONNECTICUT, ASSIGNOR TO THE OTAKA FABRIC COMPANY, OF WEST HARTFORD, CONNECTICUT, A CORPORATION OF CONNECTICUT.

PAPER-CRINKLING MACHINE.

Application filed March 18, 1927. Serial No. 176,424.

This invention relates to the method of and apparatus for crinkling and corrugating paper.

The aim of the present invention is to provide an improved method and a simple and effective machine for expeditiously and economically crinkling and corrugating paper so as to make it elastic in all directions.

10 A further aim of the invention is to provide an improved method of, and a simple and effective apparatus for, first crinkling the paper across the sheet and immediately thereafter, and while the crinkled paper is 15 still wet, longitudinally corrugating it without injury thereto.

Other objects will be in part obvious and in part pointed out more in detail hereinafter.

20 The invention accordingly consists in the features of construction, combination of elements and arrangement of parts which will be exemplified in the construction herein-after set forth and the scope of the application of which will be indicated in the appended claims.

In the accompanying drawings:

Figure 1 is a plan view of the apparatus;

Fig. 2 is a sectional view taken substantially on line 2—2 of Fig. 1;

Fig. 3 is an enlarged detail view of a portion of the crinkling and corrugating elements shown in Fig. 2, the crinkled and corrugated paper being illustrated;

Fig. 4 is a detail view of portions of the crinkling and corrugating elements shown in Fig. 3 with the paper removed;

Fig. 5 is a view similar to Fig. 3 but showing a slightly different embodiment 40 and the paper being omitted;

Fig. 6 is a partial detail view of what is shown in Fig. 5 with the paper illustrated between the corrugating elements; and

Fig. 7 is an enlarged sectional view of 45 portions of the roll 29 and the doctor blade, this view being taken substantially on line 7—7 of Fig. 3.

In the drawings, 10 and 11 designate the uprights of the frame which may be tied together in any suitable way. The numeral 12 designates the roll of paper carried by a shaft 13 supported in brackets 14 at one end of the machine. The paper passes from the roll 12 over the guide roll 15 and under

a pair of rolls 16 located in a tank 18 containing water. The paper web then passes upwardly, as at 20, onto a cylinder 21 against which it is pressed by a rubber faced roll 22. The gudgeons of the roll 22 are mounted in suitable slidable bearings 23 behind which are adjustable springs 24 so that the pressure with which the roll bears against the cylinder may be varied at will. This roll squeezes excess water out of the paper and causes the paper to hug or adhere to the cylinder.

The paper is carried by the roll 21 against the forward edge 25 of a doctor blade. Co-operating with this blade is a roller 29 which, in Figs. 2 and 3, is located immediately above the edge 25 of the doctor blade. The doctor blade, immediately behind the edge 25 and between the points 25 and 30, is relatively straight and is then curved, as at 31, correspondingly to the curvature 75 of the roller 29. Thus, there is provided between the doctor blade and the roller a relatively narrow, uniform channel. The doctor blade preferably forms the front face or wall of a hollow box 32 which is preferably heated by steam which may be supplied by a pipe 33. The roller 29 may also be heated by steam or other medium supplied through a pipe 34.

The roller 29 is circumferentially corrugated and the curved face 31 of the doctor blade is also corrugated so as to match the configuration of the periphery of the roller 29. In the drawings, the roller 29 is shown as having circumferential ribs 36 and 90 grooves 37 which are respectively opposite to the grooves 27 and the ribs 26 provided in the front face of the doctor blade. 38 designates a roller cooperating with the roller 29, and this roller 38 is also corrugated with its corrugations meshing with the corrugations of the roller 29. The corrugated roll 29 and the corrugated surface of the doctor blade are so spaced apart that the creped paper, as shown in Fig. 7, engages 100 the tops of the corrugations or ribs 26 and 36 and the crinkled paper is not forced to the bottom of the grooves 27 and 37.

The operation of the machine is briefly as follows: The paper is carried by the cylinder 21 against the edge 25 of the doctor blade, resulting in crinkling of the paper. The crinkled paper then passes over the smooth

and ungrooved portion of the doctor blade between the points 25 and 30 and then between the roller 29 and the grooved portion 31 of the doctor blade. Owing to the co-operating corrugations on the roller 29 and the curved surface 31 of the doctor blade, the crinkled paper, passing therebetween, is longitudinally corrugated while the paper is still wet. The crinkled and longitudinally corrugated paper is gripped by the rollers 29 and 38 and passes over a guide roller 39. It is important to note that the paper is corrugated immediately after it is crinkled and while the paper is still wet, the crinkling and corrugating operations being continuous; that is, without interrupting the movement of the paper. Furthermore, since the paper is not forced down to the bottom of the grooves in the corrugating members, the crinkled paper is only partially corrugated so to speak and injury to the paper is prevented. The paper, however, is sufficiently corrugated to make it transversely elastic. It will be seen, particularly from Fig. 7, that during the corrugating operation, the convex surface of the corrugations in the paper are not pressed upon by, nor engaged with, the corrugating rollers.

In the embodiment shown in Figs. 5 and 30 6, the parts are respectively similar to the corresponding parts shown in the preceding embodiment. In this instance, however, the roller 29, instead of being positioned immediately over the edge 25 of the doctor blade, is spaced rearwardly of that point an appreciable extent. As in the preceding embodiment, the paper will be crinkled when it strikes the edge 25 of the doctor blade and will be corrugated as it is passed between 40 the co-operating corrugated surfaces of the roller 29 and the doctor blade.

As many changes could be made in the above construction and many apparently widely different embodiments of the invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. The herein described method of making paper elastic in all directions, which consists in crinkling a wet paper web laterally and forming longitudinally extending grooves in the crinkled paper while it is still wet.

2. The herein described method of making paper elastic in all directions, which consists

in transversely crinkling a paper web while wet, and immediately thereafter and while the crinkled paper is wet and heated longitudinally corrugating the crinkled paper.

3. The herein described method of making paper elastic in all directions, which consists in transversely crinkling a wet paper web by moving the same against the edge of a doctor blade, and longitudinally corrugating the crinkled web while wet by passing the wet crinkled paper between corrugating members immediately adjacent the crinkling edge.

4. The herein described method of making paper elastic in all directions, which consists in wetting a paper web, crinkling the wet web by moving the same against the edge of a doctor blade, and then immediately corrugating the crinkled web while wet and without interrupting its movement by passing the same between a corrugated roller and a co-operating corrugated surface.

5. The herein described method of making paper elastic in all directions, which consists in first crinkling the paper laterally, and then forming partial longitudinal grooves in the laterally crinkled paper while the paper is still wet.

6. The herein described method of making paper elastic in all directions, which consists in first crinkling the wet paper web laterally and then longitudinally corrugating the crinkled paper while still wet by passing the same between corrugating members and without engaging the convex surfaces of the corrugations.

7. In a machine for making paper elastic in all directions, means for laterally crinkling the paper, and means for immediately thereafter forming longitudinal corrugations in the paper.

8. In a machine for making paper elastic in all directions, a doctor blade, means for moving a paper web against the doctor blade to laterally crinkle the paper, and means immediately behind the crinkling edge of the doctor blade for corrugating the paper.

9. In a machine for making paper elastic in all directions, a crinkling cylinder, a doctor blade cooperating therewith and having a corrugated curved face rearwardly of the crinkling edge, and a corrugated roller concentric to said face.

10. In a machine for making paper elastic in all directions, a crinkling cylinder, means for moistening a paper web delivered thereto, a doctor blade cooperating with said cylinder and having rearwardly of its crinkling edge a corrugated curved surface, a corrugated roller cooperating with said surface for corrugating the paper passing between said roller and surface, and means for heating said roller and surface.

11. In a machine for making paper elastic

in all directions, means for laterally crinkling the paper, and means for longitudinally and partially grooving the laterally crinkled paper.

5 12. In a machine for making paper elastic in all directions, means for wetting a paper web, means for laterally crinkling the wet paper web, and means for forming partial longitudinal grooves in the laterally crinkled web while the same is still damp.

10 13. In a machine for making paper elastic in all directions, means for crinkling a paper web transversely, and means for longitudinally corrugating the crinkled web, said corrugating means being arranged to corrugate

the crinkled paper without engaging the convex surfaces of the ribs formed in the paper.

14. In a machine for making paper elastic in all directions, means for wetting a paper web, a doctor blade for transversely crinkling the wet web, and corrugated members for longitudinally corrugating the crinkled web while still damp, said members being arranged so that the paper will engage the tops of the corrugations on said members and will not be forced into engagement with the bottoms of grooves between the corrugations. 20 25

WILLIAM A. LORENZ.
